ABRADING APPARATUS

Walter L. Keefer, Hagerstown, Md., assignor to
 Pangborn Corporation, Hagerstown, Md., a corporation of Maryland

Application October 25, 1941, Serial No. 416,577

18 Claims. (Cl. 51—9)

This invention relates to abrading apparatus, and more particularly to a centrifugal wheel for projecting abrasive, such as steel grit and shot, at an abrading velocity upon workpieces to be cleaned.

Machines of the type herein described may be said to consist of three main parts, namely, a rotor having one or more abrasive propelling blades, an abrasive supply means, and a transfer mechanism which functions to transfer the abrasive from the supply means to the blade, or blades, of the rotor in such manner that the abrasive is discharged onto the inner ends of the blades at a predetermined point or zone, the abrasive subsequently being discharged from the ends of the blades in a predetermined zone.

In providing an improved centrifugal wheel for throwing abrasive, it is a major object of this invention to provide a novel transfer means which is designed to receive abrasive from suitable abrasive feed means, the abrasive being transferred almost simultaneously to the inner ends of the throwing blades of the rotor.

A further object of this invention is the provision of a novel transfer means arranged to receive abrasive from a feed means and transfer it immediately onto the inner ends of the blades of the rotor at a predetermined point or zone with a minimum of dispersion.

Still a further object of this invention is the provision of a novel transfer mechanism for a centrifugal wheel wherein the abrasive fed by the feed means is transferred at a maximum velocity onto the inner ends of the throwing blades at a predetermined point or zone, the transfer occurring at substantially the point of feed whereby the abrasive is in contact with the transfer mechanism for only a very short period of time, and friction, and consequently the power required to drive the mechanism is reduced to a minimum.

A further object of this invention is the provision of novel transfer and feed mechanism wherein a chamber eccentric or at one side of the axis of the rotor is provided to receive the abrasive in combination with means operative in the chamber to transfer the abrasive almost simultaneously and at a substantial velocity onto the inner ends of the throwing blades of the rotor, the discharge being in a direction to enable the abrasive to be picked up thereby with a minimum of impact.

Still a further object of this invention is the provision of a centrifugal throwing wheel of novel construction wherein the parts are relatively simple, of long life, and easily accessible for replace-

ment and repair, the several parts of the wheel being readily adjustable to vary the direction of discharge of abrasive from the wheel.

Further objects and advantages of this invention will appear from the following description and claims taken in connection with the appended drawings, wherein

Fig. 1 is a front elevation of a centrifugal abrading wheel embodying the present invention, taken on the line 1—1 of Fig. 2, the housing being omitted.

Fig. 2 is a section taken on the line 2—2 of Fig. 1 with portions of the front and rear walls of the housing shown in section, and the feed spout shown in outline, the feed spout not being visible in a true section taken on the line 2—2 because of its offset with respect to a vertical line through the center of the wheel, as evident from Fig. 4.

Fig. 3 is an exploded view of the several parts of the wheel of Figs. 1 and 2 in side elevation.

Fig. 4 is a front elevation of the feed spout of the wheel of Figs. 1 and 2 shown in combination with portions of the holder, the spout being shown in the position it would occupy in a "down" blast wheel.

Fig. 5 is a rear elevation of the lower part of the feed spout of Fig. 4.

Fig. 6 is a front elevation of the holder for the guard and feed spout of the wheel.

Fig. 7 is a perspective of the impeller of the wheel of Figs. 1 and 2.

Fig. 8 is a front elevation of the guard of the wheel.

Fig. 9 is an elevation of a portion of the guard of Fig. 8 looking in the direction indicated by the arrow 9.

Fig. 10 is a rear elevation of the guard of Fig. 8.

Fig. 11 is an elevation of a portion of the guard of Fig. 10 looking in the direction indicated by the arrow 11.

Referring to Figs. 1 and 2, the centrifugal abrasive throwing wheel there illustrated includes three main elements, namely, a rotor R, an abrasive feed means F, and a transfer mechanism T.

The wheel is preferably surrounded by a housing having end walls (not shown), and front and rear walls 10 and 12. Preferably wear plates 13, as shown in Fig. 2, are provided on the interior 50 of the housing walls to prevent damage thereto by the flying abrasive.

The rotor R comprises a flange 14 mounted on a rotatable shaft 14, driven by any suitable means such as an electric motor (not shown).

Flange 14 has a centering flange 15 thereon and

a relatively heavy disc 16 having radial grooves therein to receive and support a series of channel-shaped blades 17, said blades being preferably sharpened at their inner ends, as shown in Fig. 1 'at 18, to facilitate their cutting through the abrasive stream from the transfer mechanism. For a detailed description of such rotors and the manner of securing the blades thereto, attention is directed to Patent No. 2,108,211, issued on February 5, 1938.

The abrasive feed means F includes a feed spout 19 arranged to receive abrasive fed by gravity, as from an elevated hopper, and conduct the abrasive to the transfer mechanism T. Spout 19 is provided with a flange 21 at its upper end for attachment to a suitable support and a flange 22 at its lower end. The lower end of the spout is adapted to enter an aperture 23 formed in a holder 24 (Figs. 3 and 4). Flange 22 (Fig. 4) is engaged by a clamp 25 secured by a bolt 26 passing through a threaded hole in holder 24, this arrangement serving to hold the lower end of the feed spout in its proper position. As flange 22 and aperture 23 are circular, the feed spout can be fitted in the holder regardless of the clock dial position of aperture 23 relative to the center of the holder.

The discharge opening 21 of feed spout 19 (Fig. 5) is bounded by a shield or trough 28 for approximately 180°, the shield being of diameter to fit within an aperture 29 in a guard member 31. Shield 28 functions to maintain the discharge opening of the feed spout centered in aperture 29. In the assembled position, shield 28 preferably extends to the inner edge of bevel 29' of aperture 29, Fig. 9, to insure that the abrasive is conducted past aperture 29 to a point where it can be positively acted upon by the blades of the impeller mechanism, to be described.

The feed spout 19 is provided with an opening 31' in its upper side which increases the capacity of the mechanism for abrasive. Ordinarily, as the stream of abrasive discharged by the feed spout is cut into wads by the impeller blades, there is some ricochet of the abrasive which tends to block the discharge end of the feed spout. This ricochetting is kept to a minimum by a current of air induced through opening 31' by the rotation of the impeller and blades 17, this current of air flowing over the top of abrasive passing through the feed spout. This current of air catches the abrasive particles that would otherwise block the feed spout and carries them back into the impeller, which accomplishes their discharge.

The holder 24 is of generally circular shape and provided with a cylindrical section 32 arranged to fit within an opening 33 in wall 10 and the attached wear plate 13. A flange 34 is provided on holder 24 to fit against a ring 35 preferably welded to the inside of wall 10, as indicated at 36, and held thereagainst by suitable means, such as clamps, whereby the holder may be rotated to position aperture 23 and the feed spout secured therein in different positions about the axis of the rotor. Such clamps are disclosed in my copending application Serial No. 324,860, filed March 19, 1940.

To facilitate adjustment of guard member 31, which is secured to holder 24, a plurality of removable shims 37 are preferably provided between flange 34 and ring 35. By adjusting the number and size of the shims, the position of guard member 31 within the central portion of the wheel can be adjusted axially of the assembly.

The guard member 31 comprises a disc 38 secured to holder 24 by bolts countersunk in the disc at 39 and passing through holes 41 in the holder. Disc 38 is formed with aperture 29 which receives shield 28 so that the abrasive passes from the discharge opening of the feed spout into the interior of the wheel in a generally uninterrupted stream.

The disc 38 is formed with a peripheral flange 42 and a central boss 43 which serve to seat the disc against holder 24. Aperture 29 is bounded by a boss 44 which also seats against the holder. As is evident from Fig. 9, the wall portion 45 defining the smallest portion of aperture 29 is not flush with the face of disc 38, but is some distance below the face of the disc. From wall portion 45, a curved surface or groove 46 is provided curving outwardly to the face of the disc. The degree of curvature of this groove is indicated by the lines A, B, and C of Fig. 9, which are taken on the arcs A, B, and C of Fig. 8, respectively.

The groove 46 functions to receive some of the batted abrasive as the vanes of the impeller cut through the stream of abrasive. It has been found that the edges of the blades interrupt some abrasive and push it back against disc 38. As this abrasive has some forward velocity, it travels along the groove 46 and returns to the impeller vanes. In the absence of such a groove, it has been found that sufficient abrasive will accumulate in a short time to block the feed spout an appreciable amount.

The groove 46 terminates at a ridge or rib 47 (Fig. 10). From ridge 47 to the periphery of the disc, the disc surface is formed with a series of relatively deep grooves 48, extending normally from ridge 47 to the periphery of the disc. Grooves 48 function to collect stray particles of abrasive traveling between the impeller vanes and disc 38, and transfer them into the path of the rotor blades adjacent the discharge point of the main stream from the impeller. Otherwise, it has been found that a large percentage of these particles will continue to travel around the face of disc 38 and discharge at other than the desired zone.

A portion of the outer periphery of the guard disc section, which includes aperture 29 and groove 46, is bounded by an arcuate shaped flange or guard 49 which extends from a point adjacent the ridge 47 to the far edge of aperture 29, or through an arc of about 115°. The outer end of guard 49 is preferably provided with an inwardly extending flange 51, so that the inner surface of the guard is formed in the shape of a channel.

An outwardly projecting hollow cylindrical boss 52 is provided at the center of the guard disc 38 opposite boss 43, boss 52 being closed at its outer end at 53 and formed with a slot 54 facing aperture 29. Slot 54 preferably extends through about 180°.

An aperture 55 is provided in disc 38 in line with the hollow section of boss 52 and an opening 56 formed in the center of holder 24. As shown in Fig. 2, this arrangement provides for an unrestricted access of air to slot 54, which aids in the flow of the abrasive, as later described.

An annular groove 57 in the face of disc 38 is provided about the outer periphery of boss 52 for a purpose to be later described.

The impeller or transfer mechanism proper shown in Figs. 1, 2, 3, and 7 at 58 includes a hollow cylindrical section 59 having an enlarged

portion 61 on the end thereof arranged to be fitted within a central recess 62 formed in disc 16 and against centering flange 15, the impeller being secured in position by a bolt 63 (Fig. 2) entering flange 14 so that the impeller rotates with rotor R. Preferably bolt 63 passes through an internal boss 64 formed in the center of section 59. To insure the impeller 58 being always assembled in the same relative position with disc 16, a slot 65 is cut in the periphery of section 61 to fit over the head of a bolt 66 which is secured in disc 14.

The left face of section 59 as viewed in Figs. 3 and 7 is closed by a solid wall 67 which has a series of vanes 68 and 69 secured thereto, each vane extending in a substantially radial direction with its inner ends spaced sufficiently from the center to clear the outer periphery of boss 52 in operation.

Vanes 68 and 69 are preferably arranged alternately around the impeller, there being four vanes of each type on the illustrated embodiment, making a total of eight vanes. It is preferred to have the same number of vanes on the impeller as blades 17 on the rotor, and to position the impeller so that each impeller vane leads its corresponding rotor blade by approximately 15°, measuring from the center lines of the vane and the blade. This position of the impeller is insured by slot 65 and bolt 66.

Each of vanes 68 progressively increases in width from its inner end to its outer end, the latter being defined by an edge 71 substantially parallel to the face of wall 67. A flange 72 is provided along the outer edge of each vane 68 extending upwardly from the abrasive contacting face 73 to confine the abrasive to the throwing face of the vane and prevent its escape therefrom.

Each of vanes 69 has its widest section adjacent the center of the impeller, the narrowest section being at the outer periphery of the impeller. Thus vanes 68 and 69 taper in opposite directions. Each vane 69 has its inner and widest end defined by an edge 74 parallel to edges 71 of vanes 68, and is also provided with a flange 75 serving the same purpose as flange 72.

Each vane 69 is formed on its inner end adjacent the hollow center defined by the inner ends of the vanes with an axially extending generally wedge-shaped lug 76 which, as shown in the assembly of Fig. 2, fits within annular groove 57 of the guard with a running clearance. When the wheel is operating, lugs 76 cooperate with groove 57 to form a seal against the escape of abrasive.

In operation, abrasive is fed through feed spout 19 and discharged through opening 27 in a direction substantially normal to the plane of rotation of impeller 58, the latter rotating with rotor R. As the abrasive is discharged in a substantially continuous stream, it encounters vanes 68 and 69 which divide it into a series of separate wads or charges.

The abrasive charges are given a velocity in the direction of movement of the impeller vanes, and are discharged from the zone in which the impeller operates at a point adjacent the end of guard 49 onto the inner ends of blades 17, the direction of discharge and the speed of the particles being such that the abrasive is picked up by blades 17 with a minimum of impact.

The guard 49, groove 46, and grooves 48 function to return the stray particles of abrasive to the impeller vanes or the path of the main

stream, so that the resultant feed of abrasive onto the inner ends of blades 17 will be substantially at one point.

By reason of the rotation of the impeller and the rotor blades, an appreciable current of air is induced through opening 54 in boss 52 of the guard member. This air current has been found to prevent any downward leaking of stray abrasive. This air current also, as well as the air induced through opening 31' in the feed spout, aids in preventing blocking of the feed spout.

The impeller with its alternately tapered vanes has been found to actually increase the capacity of the transfer mechanism for abrasive as compared with an impeller having non-tapered blades, or having all blades taper in one direction. This can only be explained at this time by the fact that with blades of alternate tapers, there is less tendency to push abrasive back into the feed spout and block or choke the spout.

The described structure is of particular advantage in that the abrasive fed into the transfer mechanism travels therethrough only a relatively short period of time, and is almost simultaneously discharged therefrom. This results in a minimum expenditure of power as distinguished from a device employing a circumferential cage wherein the abrasive is carried around and around in the cage, and results in a minimum of wear because of the relatively short time the abrasive is in contact with the transfer mechanism.

In actual tests, it has been found that the herein-described mechanism abrades or cleans work-pieces more uniformly than prior wheels.

The wheel herein-described is universal in character in that the feed spout, the holder, and the guard member are capable of adjustment so that the discharge of the abrasive from the rotor blades can be secured in any desired direction.

It is to be understood that the invention may be embodied in specific forms other than that illustrated without departing from the principle or essential characteristics thereof. The embodiments shown are therefore to be considered as illustrative and not restrictive, the scope of the invention being defined by the appended claims rather than the foregoing description and drawings. All modifications and changes which come within the meaning and range of equivalency of the claims are therefore intended to be included therein.

I claim:

1. In an abrading apparatus, a rotor having a plurality of abrasive propelling blades, the inner ends of said blades being spaced apart to define a central opening, an impeller in said central opening comprising two series of vanes mounted to rotate about the axis of said rotor, the vanes of one series being tapered in a direction to provide a vane having a greater width at its outer end than at its inner end, the vanes of the other series being tapered in a direction to provide a vane having a greater width at its inner end than at its outer end, and means to feed abrasive over the side edges of said vanes.

2. An abrasive feed and transfer mechanism for use with a centrifugal abrading rotor comprising an abrasive feed spout, a disc-like member surrounding the discharge end of said feed spout, and a rotatable impeller secured to said rotor to intercept the abrasive discharged from the discharge end of said feed spout, said disc-like member being formed with a plurality of grooves therein adjacent the impeller extending in a direction substantially parallel to the direction of discharge of abrasive by said impeller.

3. An abrasive feed and transfer mechanism for use with a centrifugal abrading rotor comprising an abrasive feed spout having its discharge end eccentric of the axis of said rotor, a member having a substantially flat surface surrounding the discharge end of said feed spout and facing in the direction of discharge from said spout, and means to intercept the abrasive discharged from said feed spout and discharge it in a direction substantially parallel to the flat surface of said member, said surface being formed with a plurality of grooves extending in a direction substantially parallel to the direction of the abrasive discharged by said last mentioned means.

4. An abrasive feed and transfer mechanism for use with a centrifugal abrading rotor comprising an abrasive feed spout having its discharge end eccentric of the axis of said rotor, a member having a substantially flat surface surrounding the discharge end of said feed spout and facing in the direction of discharge from said spout, and means to intercept the abrasive discharged from said feed spout and discharge it in a direction substantially parallel to the flat surface of said member, said surface being formed with a relatively large groove beginning adjacent said feed spout and decreasing in depth to a point spaced from said feed spout in the direction of movement of said abrasive.

5. A transfer mechanism for use with a centrifugal abrading rotor comprising an impeller having two series of vanes mounted to rotate about the axis of said rotor, the vanes of one series being tapered in a direction to provide a vane having a greater width at its outer end than at its inner end, the vanes of the other series being tapered in a direction to provide a vane having a greater width at its inner end than at its outer end, the vanes of the two series being alternately arranged.

6. An abrasive feed and transfer mechanism for use with a centrifugal abrading rotor comprising, a boss substantially aligned with the axis of said rotor, a rotatable impeller including a plurality of vanes arranged around and adapted to revolve about said boss, means for feeding a stream of abrasive over lateral edges of said vanes at a position offset from said boss, and said boss having a passage therein terminating in a slot of limited peripheral extent for directing a current of air across the abrasive stream.

7. An abrasive feed and transfer mechanism for transferring abrasive onto the propeller blades of a centrifugal rotor comprising, a plurality of impeller vanes rotatable with said rotor and extending inwardly short of the axis of the rotor to define a central space, a disc at one end of the impeller vanes, a boss carried by said disc extending into said central space, said disc having an aperture therein radially displaced from the axis of the rotor, means for supplying abrasive through said aperture over edges of the impeller vanes, and said boss and said disc having a passage therein terminating in a slot in the boss of limited peripheral extent for directing a current of air across said aperture.

8. An abrasive feed and transfer mechanism for transferring abrasive onto the propeller blades of a centrifugal rotor comprising, a plurality of impeller vanes rotatable with said rotor and extending inwardly short of the axis of the rotor to outline a central space, closure means at one end of the impeller vanes, a boss carried

by said closure means extending into said central space, said closure means having an aperture therein radially displaced from the axis of the rotor, a feed spout for supplying abrasive through said aperture over edges of the impeller vanes, said boss and said closure means having a passage therein terminating in a slot in the boss of limited peripheral extent for directing a current of air across said aperture, and the upper side of said feed spout having an opening therein adjacent said closure means.

9. An abrasive transfer mechanism for transferring abrasive onto the inner ends of propeller blades at a predetermined point in the rotation thereof comprising, an impeller including a plurality of vanes extending inwardly short of the axis of the impeller to define a central space, a disc at one end of the impeller vanes, a hollow boss extending from the disc into said central space, said disc having an aperture therein radially offset from the axis of the impeller, means for feeding abrasive through said aperture over the edges of said impeller vanes, said boss having a peripheral slot therein for directing a current of air developed by the rotation of the impeller vanes across said aperture, and a relatively short arcuate shaped guard carried by the disc extending over the impeller vanes radially of said aperture.

10. A mechanism for transferring abrasive onto the inner ends of propelling blades of centrifugal abrading apparatus comprising, a rotatable impeller including a plurality of vanes, a stationary disc mounted adjacent one end of said impeller vanes, said disc having an aperture extending therethrough at a point offset from the axis of said impeller, means for supplying abrasive through said aperture and over the edges of said vanes, the face of said disc adjacent said vanes having an arcuate groove therein extending from said aperture and decreasing in depth in the direction of rotation of said impeller vanes.

11. A mechanism for transferring abrasive onto the inner ends of propelling blades of centrifugal abrading apparatus comprising, a rotatable impeller including a plurality of vanes, a stationary disc mounted adjacent one end of said impeller vanes, said disc having an aperture extending therethrough at a point offset from the axis of said impeller, means for supplying abrasive through said aperture and over the edges of said vanes, the face of said disc adjacent said vanes having a groove therein extending from said aperture and decreasing in depth in the direction of rotation of said impeller vanes to a point circumferentially spaced from said aperture, and said disc having a plurality of substantially parallel grooves therein extending in a chordal direction from the end of the first groove to the periphery of said disc.

12. A mechanism for transferring abrasive onto the inner ends of propelling blades of centrifugal abrading apparatus comprising, a rotatable impeller including a plurality of radial vanes, a stationary disc mounted adjacent one end of said impeller vanes, said disc having an aperture extending therethrough at a point offset from the axis of said impeller, means for supplying abrasive through said aperture and over the edges of said vanes, the face of said disc adjacent said vanes having an arcuate groove therein extending from said aperture and decreasing in depth in the direction of rotation of said impeller vanes to a point circumferentially spaced from said

aperture, and an arcuate shaped guard extending along the periphery of said disc a sufficient distance to embrace said aperture and said groove.

13. A mechanism for transferring abrasive onto the inner ends of propelling blades of centrifugal abrading apparatus comprising, a rotatable impeller including a plurality of radial vanes, a stationary disc mounted adjacent one end of said impeller vanes, said disc having an aperture extending therethrough at a point offset from the axis of said impeller, means for supplying abrasive through said aperture and over the edges of said vanes, the face of said disc adjacent said vanes having a groove therein extending from said aperture and decreasing in depth in the direction of rotation of said impeller vanes to a point circumferentially spaced from said aperture, said disc having a plurality of substantially parallel grooves therein extending in a chordal direction from the end of the first groove to the periphery of the disc, an arcuate shaped guard extending along the periphery of said disc a sufficient distance to embrace said aperture and said groove, said disc having a passage therethrough substantially aligned with the axis of said impeller, and means associated with said passage for directing air drawn through said passage towards said aperture.

14. A mechanism for transferring abrasive onto the propeller blades of a centrifugal rotor comprising, an impeller mounted for rotation about the axis of the rotor including a cylindrical section and a radial wall with two series of vanes carried by and extending laterally from said wall, the free edges of the vanes of one series tapering in one direction and the free edges of the vanes of the other series tapering in an opposite direction, a flange carried by and following the free edge of each vane, and means for feeding abrasive over the free edges of said vanes.

15. In abrading apparatus, a rotor including a plurality of propeller blades terminating inwardly short of the axis of the rotor, an impeller rotatable with said rotor arranged between the inner ends of said propeller blades including a plurality of radially arranged vanes having free lateral edges, a stationary arcuate shaped guard having a circumferential length of less than one-half the circumference of the impeller mounted between the path described by the inner ends of said propeller blades and the path described by the outer ends of said impeller vanes, and a feed spout terminating adjacent the free lateral edges of said impeller vanes having a discharge opening in the terminal end located within a sector defined by the circumferential ends of said guard and at a position radially displaced from the axis of the impeller for supplying abrasive axially over the free lateral edges of the impeller vanes and onto outer end portions of the impeller vanes whereby the abrasive is discharged from the impeller vanes adjacent an end of said guard.

16. In abrading apparatus, a rotor including a plurality of propeller blades terminating inward-

ly short of the axis of the rotor, an impeller rotatable with said rotor and arranged between the inner ends of said propeller blades, said impeller including an end wall and a plurality of 5 radially arranged vanes extending laterally from said end wall terminating in free edges within planes defined by the edges of said propeller blades, a stationary arcuate shaped guard having a circumferential length of approximately one-third the circumference of the impeller mounted between a path described by the inner ends of said propeller blades and a path described by the outer ends of said impeller vanes, and a feed spout terminating adjacent the free edges of said impeller vanes within a sector defined by the ends of said guard and at a position 10 radially displaced from the axis of the impeller for supplying a stream of abrasive axially over the free edges of the impeller vanes whereby the abrasive issuing from the feed spout is supplied to outer end portions of the impeller vanes as they pass one end of the guard and the abrasive is discharged from the impeller vanes as they pass the other end of said guard.

17. A mechanism for transferring abrasive onto the inner ends of propeller blades of centrifugal abrading apparatus comprising, a rotatable impeller including a plurality of radial vanes having free lateral edges, normally stationary adjustable means covering the free edges of said vanes, said means having an aperture extending therethrough at a point offset from the axis of the impeller, means for supplying abrasive through said aperture and axially over the free lateral edges of said vanes, an arcuate shaped guard carried by said means adjacent said aperture embracing the periphery of said impeller for a distance of approximately 115 degrees, and said aperture having a radial extent less than the radius of the impeller and a circumferential extent less than the circumferential length of said guard.

18. A mechanism for transferring abrasive onto the inner ends of propeller blades of centrifugal abrading apparatus comprising, a rotatable impeller including a plurality of substantially radial vanes having free lateral edges, normally stationary adjustable means covering the free edges of said vanes, said means having an aperture 45 extending therethrough at a point offset from the axis of the impeller, means for supplying abrasive through said aperture and axially over the free lateral edges of said vanes, an arcuate shaped guard carried by said means extending circumferentially over the periphery of the impeller and terminating in an edge positioned less than 50 180 degrees forwardly of said aperture measured in the direction of rotation of said impeller, and said aperture having all radial dimensions thereof less than the radius of the impeller and a circumferential extent less than the arcuate length of said guard.

WALTER L. KEEFER.
